UNITED STATES PATENT OFFICE

2,224,439

APPARATUS FOR EARTH BORING

Robert E. Lee, Coleman, Tex., assignor of fifty per cent to Joseph H. Reynolds, Cisco, Tex.

Application December 13, 1937, Serial No. 179,569

4 Claims. (Cl. 255—4)

This invention relates to earth boring and it has particular reference to a method and apparatus for drilling oil, gas and water wells.

The principal object of the invention is to provide a method and apparatus whereby the efficiency of the drilling tool is increased, particularly when hard formations are encountered.

Another object of the invention is to provide a mechanism within the drill stem whereby a succession of blows or impulses are imparted to the drill bit, thereby causing a shattering action on the formation encountered.

Still another object of the invention is to provide a mechanism at the surface of the earth whereby the rate and force at which the impulses delivered to the bit is under the control of an operator at all times.

Yet another object of the invention is to provide electromagnetic means for imparting impulses to a drill bit, which means are controlled from the surface of the earth, and are so arranged that the said means do not interfere with the normal operations of drilling, such as running in and coming out of the bore hole.

Still another object is to provide means whereby the hydraulic cushion heretofore present between the face of the drilling bit and the formation is eliminated.

A still further object is to provide a mechanism whereby much less weight is required on the drilling bit as compared to present weights necessary to accomplish efficient drilling results.

With the foregoing objects as paramount, the invention has particular reference to its salient features of construction and arrangement of parts, which will become manifest as the description proceeds, taken in connection with the accompanying drawings, wherein:

Figure 1 is a fragmentary elevational view of a conventional derrick, shown with the swivel and rotary table, and showing the control equipment and the lead cables attached thereto.

Figure 2 is an enlarged sectional view of the bore hole, shown with the casing and drill stem, and showing the insulated electric power cable within the drill stem.

Figure 3 is a cross sectional view of the power cable.

Figure 4 is an elevational view of the cable reel.

Figure 5 is a view taken on the line 5—5 on Figure 4, shown with portions broken away.

Figure 6 is a fragmentary view of the structure whereby electric power is transmitted to the cable on the reel shown in Figure 4.

Figure 7 is a diagrammatic view of the appa-

ratus for generating an electric current and for transmitting the same alternately to the electromagnets within the drill stem, and showing the means for varying the rate of alternation.

Figure 8 is a cross sectional view of one of the 5 commutators shown in Figure 7.

Figure 9 is a similar view of the companion commutator.

Figure 10 is a cross sectional view of the slip ring assembly.

Figure 11 is a view in vertical section of the apparatus within the drill stem for making electrical contact between the electric power cable and the assembly therebeneath, and also showing the packing unit.

Figure 12 is a view taken on the line 12—12 on Figure 11.

Figure 13 is a view in vertical section of the assembly into which the unit shown in Figure 11 is operatively received, and showing the electrical contacts and connecting wires positioned therein.

Figure 14 is a view taken on the line 14—14 on Figure 13.

Figure 15 is a view taken on the line 15—15 on Figure 13.

Figure 16 is a view in vertical section of the lower part of the assembly and showing fragmentarily the electromagnets, hammer and the rock bit.

Figure 17 is a view in vertical section of the upper part of a modified form of the invention and showing the electrical connections within a standard drilling tool.

Figure 18 is a fragmentary diagrammatic view 35 of the commutator assembly for supplying current to the modified form of the invention shown in Figure 17.

Figure 19 is a fragmentary view in vertical section of the lower part of the assembly shown in 40 Figure 17, and showing fragmentarily a conventional standard bit, and

Figure 20 is an elevational view of a mud pump, and showing a discharge or bleeder valve arrangement.

Continuing with a more detailed description of the drawings, 1 denotes a conventional derrick used in the drilling of oil and water wells. The drill stem assembly is raised and lowered by a cable 2 which passes through a block 3 to which 50 a swivel 4 is attached as shown. A kelly joint 5 is attached to the swivel 4 and passes through a conventional rotary table 6.

It will be understood that the present invention provides for a succession of electromagnets 55

cally imparted hammer blows, which blows are transmitted to a drilling bit when the bit is in contact with a formation, and further that the rate and force of the said blows are under the control of an operator at all times.

Referring to Figure 1, 7 denotes a control box which serves to encase the impulse rate changer illustrated diagrammatically in Figure 7. The rate of the impulses transmitted to the drilling bit is controlled by an operator through the medium of a control lever 8.

A reel 9, best illustrated in Figures 4 and 5, serves as a means upon which an electric power cable 10, illustrated in cross section in Figure 3 is wound. The power cable 10 is comprised of steel wires 11 which serve to encase an insulating material 12. Insulated wires 13, 14, and 15 are imbedded within the insulating material 12.

The reel 9 is rotated by a suitable source of power (not shown) through a sprocket 16. Power is applied, when required, to the reel 9 through the medium of a clutch 17 which is controlled by a rod 18.

Figure 5 is an end view of the reel 9 with portions of the housing 19 broken away and showing the slip ring arrangement. This latter assembly is comprised of the rings 20, 21 and 22, which are also shown in cross section in Figure 6. It will be seen that these rings are insulated from the reel 9 by the insulating material 23. Electrical contact is made with the slip rings above described by means of the brushes 24, 25 and 26, which brushes are spring pressed against the slip rings. As shown in Figure 6, the cable 10 is anchored or secured to the body of the reel 9 by means of a clamp 27.

As illustrated in Figure 2 the cable 10 extends downwardly into the well through the drill stem 28, and enters the latter as shown in Figure 1 through a packing member 29, which is suitably positioned on a conventional swivel 30, which swivel is connected to the conventional kelly joint 5.

Thus, it will be seen that, regardless of the position of the drill stem assembly with the well, an electrical current may be conducted within the cable 10 which is positioned within the drill stem assembly, since electrical contact is possible at all times to the slip rings 20, 21 and 22 which are positioned on and insulated from the reel 9.

Figure 7 illustrates diagrammatically one method whereby a controlled electrical current is conducted into a well, and within the drill stem assembly. A generator 31 is actuated by a suitable source of power, such as by an alternating current motor 32 which latter is supplied with current from the mains 33. A reversed cone speed changer 34 is arranged as shown, and is manually controlled by means of the lever 8 which is connected to a shifting fork or pulley 35.

A commutator assembly is shown in elevation in Figure 7, and is illustrated in cross section in Figures 8, 9 and 10. It will be understood that in order to obtain the desired hammer action upon the drill bit, it is necessary to alternately raise and force downwardly a ferrous hammer or plunger. The raising of the hammer is accomplished by means of the electromagnet 36, and the downward blow is attained by reason of the energization of the electromagnet 37. The magnet 36 is attached to the wires 14 and 15 by branch wires 76 and the magnet 37 is attached to the wires 13 and 15 by the branch wires 76'.

It will be seen that current is continuously supplied to the wire 15 which is in constant elec-

trical contact with the generator 31 through the medium of the brushes 38 which brushes contact the slip ring 39. This ring is insulated from the shaft as shown in Figure 10. A brush 40 alternately makes contact with a commutator segment 41 and a commutator segment 42. A brush 43 is in contact with the commutator shown in Figure 8, and a brush 44 is likewise in contact with the commutator shown in Figure 9. It will be understood that the commutators are insulated from each other, and from the slip ring 39. The arrangement above described serves to alternately energize the electromagnets 36 and 37, which magnets serve to effect the hammer action on the drilling bit.

Figure 11 illustrates fragmentarily a drill stem and the means within the stem for making electrical contact with the assembly shown in Figure 13.

A drill stem unit 45, serves to encase the assembly, which latter is comprised primarily of the electric power cable 10, illustrated in cross section in Figure 3. The cable 10 is mule-tailed by the metal 47, as shown. A packer 48 is arranged as shown, and is positioned intermediate the bearings 49 and 50. The purpose of these bearings is to provide a means whereby the cable 10 may remain stationary regardless of rotation of the drill stem unit 45, when the central assembly shown in Figure 11 is lowered as herein-after explained.

The wires 13, 14 and 15, shown also diagrammatically in Figure 7, are electrically connected to the rings 51, 52 and 53, respectively. These rings are electrically insulated from the metallic portions of the unit by means of insulating material 54.

Figure 13 illustrates the assembly into which the central assembly shown in Figure 11 is conformably received when it is desired to make electrical contact with the electromagnets, which magnets are preferably positioned adjacent the drill bit. The assembly shown in Figure 13 is comprised primarily of the cylindrically shaped member 55, which member is provided with a plurality of ports or water course 56. A space 57 is provided within the upper portion of the unit 55. A flexible member 58, having an annular cross section is centrally positioned within the space 57. The purpose of the flexible member 58 is to squeeze fluid from the chamber 57, and to effect a seal when the central unit shown in Figure 11 is lowered by hydraulic pressure impressed thereon.

When it is desired to impose a hammer action upon the drilling bit, the power cable 10, and its attendant assembly is lowered within the drill stem to a position such that the rings 51, 52 and 53, will contact the spring pressed brushes 59, 60 and 61, respectively. As the latter operation is effected, the packing member 58 is expanded by reason of the action of the beveled member 48, shown in Figure 11. A seal is thus effected, but it will be observed that the water course is open to the units beneath the structure above described by reason of the ports 56. It will be observed that the central assembly shown in Figure 13 is mounted upon a ball bearing 62, in order to prevent rotation of this assembly when the drill stem is rotated. A ground joint is provided at a.

Since it is necessary to provide means for making electric contact between the central and stationary units shown in Figure 13, with units which are rotated with the drill stem, slip rings 63, 64 and 65, are provided which are insulated

as shown, and are electrically connected to the brushes 59, 60 and 61, respectively. These slip rings are mounted upon the central unit which latter unit is rotatably mounted upon the bearing

5 66. Spring pressed brushes 67, 68 and 69 contact the rings 63, 64 and 65, respectively. An annular oil chamber *b* is arranged as shown. The above described assembly is held in place by a plug 70, which is threadably secured against a 10 packing member 71. It will be understood that all of the conducting cables or wires are suitably insulated.

The electrical circuit is completed to the units positioned below those hereinabove described 15 through the medium of the insulated union connection 72. An insulated cable 73 serves to conduct current from the connection 72. It will be seen that the common ground, illustrated diagrammatically in Figure 7, is led from the cable 20 73 into a central pipe or water course 74. A packing gland 75 is arranged as shown. The wires 13, 14 and 15, are provided with taps or lead wires 76 and 76', as shown in Figure 9.

The common lead wire 15 is connected to the 25 electromagnets 36 and 37, the return to the generator being effected through the wires 14 and 13, respectively. The electromagnet 36 is encased within a housing 77, which latter is sheathed by the non-ferrous shell 78. It will be understood 30 that the drill stem assembly surrounding the magnet arrangement and the hammer, to be hereinafter described, is constructed of non-ferrous material.

The water course 74 serves as a guide for a 35 ferrous hammer 79, which hammer is alternately raised by the magnetic pull of the magnet 36, and forced downwardly by the action of the magnet 37. The magnet 37 is encased within a housing 80, which latter housing is provided with a non-40 ferrous sheath 81. A conventional drill bit, such as the rock bit 82, shown in part in Figure 16, is threadably secured to the assembly as shown.

Figure 18 illustrates a conventional slush pump 83 which is provided with a valve 84. The drilling fluid enters the pump through the pipe 85 and is forced into the drill stem assembly through the pipe 86, which is connected to the swivel illustrated in Figure 1. The valve 84 is opened 45 when the assembly shown in Figure 11 is withdrawn from the well, thereby relieving back pressure 50 on this unit and allowing the drilling fluid thereabove to be discharged into the slush pit.

Figures 17, 18 and 19 illustrate a modified form 55 of the invention applicable to the standard method of drilling bore holes. Figure 17 illustrates in vertical section the electrical connections necessary to effect a hammer action upon a standard bit. It will be seen that a five wire circuit is preferably employed, as illustrated diagrammatically in Figure 18. The rate of rotation 60 of a shaft 85' is controlled by a speed changer such as illustrated in Figure 7. Manifestly, since the force of a blow imparted by an electromagnet is controlled by the amperage, surface means may 65 be employed to control the said amperage.

Referring to Figure 18, switches 86, 87, 88 and 70 89 serve to manually control current impressed upon the electromagnets 102, 102^a, 104 and 104^a, respectively. The commutators illustrated in Figure 18 are arranged in a manner similar to those illustrated in cross section in Figures 8, 9 and 10, thereby enabling an operator to control the force of the blows imparted to a standard bit through the medium of the surface switches 86, 75 87, 88 and 89. Manifestly, the rate of the im-

pulses imparted to a standard bit may be controlled by a suitable speed changer such as that illustrated in Figure 7.

Referring to Figure 17, 94 represents a standard drilling cable, through which electrical current is supplied from a reel, provided with brushes and slip rings such as illustrated in Figure 4. The cable 94 is mule-tailed by the metal 95, as illustrated in Figure 17. The above described assembly is affixed to the bit assembly 10 by means of the plug 96.

It will be seen that since springs 97 tend to exert an upward force upon the assembly as shown, the diaphragms 98 and 99 are separated when the cable 94 is in tension. Consequently, 15 the contact points 100 and 101 are out of electrical contact.

When, however, the tension on the cable 94 is released, through the normal standard drilling operation, and consequently the standard bit is 20 brought into contact with the formation, the contact points 100 and 101 are brought into electrical connection, and an electrical circuit is completed.

Thus, it will be seen that the electrical circuit 25 is completed only when the standard bit is in contact with the formation.

Referring to Figures 17 and 19, it will be seen that the force and rate of the blows electromagnetically imparted to the drilling bit is 30 under the control of an operator at all times. Furthermore, the upward lift is controlled by the electromagnets 102 and 102^a and the upward force or impulse imparted to a hammer 103 may be controlled from the surface of the earth. 35

It will be observed that the downward force imparted by electromagnetic action may be controlled by an operator through switch actions which will vary the amperage imparted to coils 104 and 104^a, as illustrated in Figure 19.

Manifestly, the construction as shown and illustrated, together with the method herein described is capable of some modification and such modification as may be construed within the scope and meaning of the appended claims is 40 also considered to be within the spirit and intent 45 of the invention.

What is claimed is:

1. An apparatus for drilling bore holes including in combination, a drill bit, a hammer, electro-magnets for actuating said hammer in a reciprocating motion, each of said electro-magnets comprising a plurality of field coils, and means for selectively energizing each of said field coils for varying the force of attraction between said 55 electro-magnets and said hammer for the production of shocks to said drill bits.

2. An earth boring tool for shattering an earth formation in advance of the drilling action of said tool including in combination a drill bit, 60 a hammer, electro-magnets for imparting a reciprocating motion to said hammer, each of said electro-magnets comprising a plurality of field coils, means for selectively energizing each of said field coils for varying the force of attraction between said electro-magnets and said hammer, and means for varying the rate of reciprocation of said hammer. 65

3. An apparatus for drilling bore holes including in combination a rotary drill bit, a hammer, 70 electro-magnets for actuating said hammer in a reciprocating motion, each of said electro-magnets comprising a plurality of field coils, means for selectively energizing each of said field coils for varying the force of attraction between said 75

- electro-magnets and said hammer, means to prevent continuous adherence of said hammer to said electro-magnets, and means for varying the rate of reciprocation of said hammer.
- 5 4. An apparatus for drilling bore holes including a bit, a hammer, electromagnets for actuating said hammer in a reciprocating motion, each of said electromagnets comprising a plurality of field coils, electrical circuits to said field
10 coils, means for selectively energizing each of

said field coils for varying the force of attraction between said electromagnets and said hammer for the production of shocks, and switching means for controlling said circuits and for automatically closing said circuits when said bit is in contact with the bottom of said bore hole and for opening said circuits when said bit is lifted therefrom.

ROBERT E. LEE.

10
